DESIGN FOR A CYCLE PEDAL

Walter J. St. Onge, Torrington, Conn., assignor
to The Torrington Company, Torrington, Conn.,
a corporation of Maine

Application February 15, 1939, Serial No. 83,010

Term of patent 14 years

To all whom it may concern:

Be it known that I, Walter J. St. Onge, a citizen of the United States, residing at Torrington, in the county of Litchfield and State of Connecticut, have invented a new, original, and ornamental Design for a Cycle Pedal, of which the following is the specification, reference being had to the accompanying drawing, forming a part thereof.

In the drawing:

Figure 1 is a top plan view of the cycle pedal showing my new design;

Figure 2 is a side elevation of the cycle pedal.

Figure 3 is an end elevation of the cycle pedal.

The circular portions of my design, shown particularly in Figure 2 are reflectors.

I claim:

The ornamental design for a cycle pedal, as shown and described.

WALTER J. ST. ONGE.
